UNITED STATES PATENT OFFICE

ERNEST JOHN HITTLE, OF COLUMBUS, OHIO

SAFETY HOISTING DEVICE

Application filed October 23, 1929. Serial No. 401,780.

This invention relates to cranes, and its general object is to provide a hoisting device that is primarily designed for handling trucks of railroad freight cars and the like in an easy and expeditious manner by a single workman with minimum effort.

Another object of the invention is to provide a hoisting device that may be employed for handling any type truck for railroad cars and the like as well as any rolling structure that can be placed adjacent the device, without fear of slippage, falling or the like, with the result the device is safe and will reduce damage and injury to machinery and workmen.

A further object of the invention is to provide a hoisting device of the character set forth, that is simple in construction, inexpensive to manufacture and install and extremely efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side elevation of my hoisting device.

Figure 2 is an end view thereof.

Figure 3 is a top plan view.

Figure 4 is a sectional view taken approximately on line 4—4 of Figure 1, looking in the direction of the arrows.

Figure 5 is a sectional view taken approximately on line 5—5 of Figure 3.

Referring to the drawings in detail, the reference numeral 1 indicates a cross bar that may be square in cross section as best shown in Figure 5, and this cross bar has its ends resting upon strips 2 secured to and between the converging uprights 3 which are arranged in pairs and have their upper ends cut away to fit the cross bar as best shown in Figure 2. The converging uprights not only

support the cross bar 1, but are secured thereto through the instrumentality of brace rods 4 which are in reality angle bars that have their ends split at their juncture of the respective flanges thereof so that one of the flanges of the lower ends, which for distinction are indicated by the reference numeral 5, is secured to the outer sides of the converging uprights, while the flanges 6 are bent at an angle with respect to the body of the brace rods and secured to the confronting faces of the uprights. These respective flanges 5 and 6 at their lower ends are secured to the uprights through the medium of bolt and nut connections as shown. The upper ends 55 of the brace rods are likewise split longitudinally for a portion of their length at the juncture of the respective flanges thereof, and these portions are indicated by the reference numerals 7 and 8. The portions 7 are secured 60 to the sides of the cross bar 1, while the portions 8 which are bent at an angle with respect to the bodies of the brace rods are secured to the underside of the cross bar, and bolt and nut connections are employed as 65 the securing means. The portions 7 are secured 70 to the sides of the cross bar 1, while the portions 8 which are bent at an angle with respect to the bodies of the brace rods are secured to the underside of the cross bar, and bolt and nut connections are employed as 75 the securing means.

Cooperating with the brace rods 4 are cross rods 9 that extend transversely of and through the respective converging uprights of the pairs as best shown in Figure 2, and 80 these cross rods 9 may have their end portions threaded to receive nuts 10.

Secured upon opposite sides of the cross bar 1 are plates 11 which have formed therewith flanges 12 that are secured to the upper 85 ends of the converging uprights, and these plates 11 as well as the flanges 12 extend below the cross bar. It will be noted that these plates are arranged in cooperating pairs, and have journaled therein the trunnions 13 of drums 14. The opposed trunnions of each 90 of the drums 14 have fixed thereto worm gears 15 that have arranged in mesh therewith worms 16 the latter being secured to or formed with shafts 17 that are journaled in 95 bearings 18. The shafts are disposed longitudinally of the cross bar 1, and have secured to the outer ends hand wheels 19. Each of the drums which in fact are also arranged in pairs, as best shown in Figure 1, have se- 100

cured thereto in the usual manner, one of the ends of chains 20 and 21. It will be noted that the chains 20 which are secured to the innermost drums have secured to the lower 5 ends chain sections 22 that carry hooks 23, while the chains 21 have secured to their lower ends hooks 24, and carried by one of the links of the chains 21 are rings 25 for the purpose of receiving the hooks 24.

10 In order to further brace the structure, I provide upon each side of the cross bar 1, truss rods 26 that have their ends passed through the converging uprights 3 and threaded to receive nuts 27. The rods 26 15 are bent downwardly toward their centers at an inclination and a cross piece 28 which is bolted to the center of the cross bar 1 extends beyond the sides of said cross bar for engagement with the rods, the latter being 20 disposed below the cross piece as best shown in Figures 1 and 4.

From the above description and disclosure of the drawings, it will be obvious that I have provided a hoisting device that is primarily 25 designed for handling trucks of railroad cars and the like, and the chain sections 22 can be secured about a truck through the medium of the hooks, while the chains 21 can be likewise secured about the trucks by 30 the hooks 24 and rings 25. The hand wheels can then be rotated for lifting the trucks to the desired height whereby work can be done thereon as will be apparent. While I have set forth that my hoisting device is primarily 35 designed for trucks of the character referred to, I want it understood that it can be employed for handling any machinery and the like that can be disposed within the radius of the chains, whereby the latter can be secured thereto.

40 It is thought from the foregoing description that the advantages and novel features of my invention will be readily apparent.

I desire it to be understood that I may 45 make changes in the construction and in the combination and arrangement of the several parts, provided that such changes fall within the scope of the appended claims.

What I claim is:

50 1. A hoisting device comprising converging uprights arranged in pairs, a cross bar supported by said uprights, strips secured to said uprights and cooperating therewith for supporting the cross bar, brace rods having 55 their ends split and arranged to be secured to the converging uprights and cross bar respectively, plates secured to said cross bar and uprights, drums journaled between said plates, flexible elements secured to said drums, article clamping means carried by said flexible elements, and manual operating means for rotating said drums.

55 2. A hoisting device comprising converging uprights arranged in cooperating pairs,

strips secured to the outer sides of said uprights adjacent the upper ends thereof, cross bars resting upon said strips and between the pairs of uprights, cross bars between the uprights of each pair and being secured thereto, brace rods formed from angle iron and being split for a portion of the length thereof at their respective ends, the lower split portions being secured upon adjacent 70 sides of the uprights, the upper split portions being secured to the outer and lower sides of the cross bar, plates secured upon opposite sides of the cross bar and arranged in pairs, drums arranged in pairs, trunnions formed with said drums and journaled in 75 said plates, worm wheels secured to one of the trunnions of each drum, worms meshing with the worm wheels, hand wheels having connection with the worms for rotating the worm gears, flexible elements secured to said 80 drums, and article securing means secured to the flexible elements.

3. A hoisting device comprising converging uprights arranged in cooperating pairs, a cross bar between said pairs of uprights and secured thereto, bracing means for said uprights, said bracing means including brace rods having split ends, one of the portions at the lower ends of the brace rods being secured to the outer sides of the uprights, the remaining portions being bent at an angle with respect to the bodies of the brace rods and secured to the confronting sides of the uprights, one of the portions at the upper 90 ends of the brace rods being secured to the outer sides of the cross bar, the remaining portions at the upper ends being bent at an angle to the bodies of the brace rods and being secured to the underside of the cross 95 bar, article handling means supported with respect to the cross bar and operating means 100 for said article handling means.

4. A hoisting device comprising converging uprights arranged in cooperating pairs, a cross bar between said pairs of uprights and secured thereto, bracing means for said uprights, said bracing means including brace rods having split ends, one of the portions at the lower ends of the brace rods being secured to the outer sides of the uprights, the remaining portions being bent at an angle with respect to the bodies of the brace rods and secured to the confronting sides of the uprights, one of the portions at the upper 110 ends of the brace rods being secured to the outer sides of the cross bar, the remaining portions at the upper ends being bent at an angle to the bodies of the brace rods and being secured to the underside of the cross 115 bar, truss rods having their ends secured through the converging uprights and bent downwardly toward the center thereof, a cross piece secured centrally of the cross bar 120 125 130

and extending beyond the sides thereof for receiving the truss rods, article handling means supported with respect to the cross bar, and operating means for said article handling means.

5 In testimony whereof I affix my signature.

ERNEST JOHN HITTLE.
